UNITED STATES PATENT OFFICE.

JOHN DEWRANCE AND GEORGE HENRY WALL, OF SOUTHWARK, ENGLAND.

REDUCING-VALVE.

No. 799,723.

Specification of Letters Patent.

Patented Sept. 19, 1905.

Application filed October 24, 1904. Serial No. 229,831.

To all whom it may concern:

Be it known that we, JOHN DEWRANCE and GEORGE HENRY WALL, of 165 Great Dover street, Southwark, in the county of Surrey, 5 England, subjects of the King of Great Britain and Ireland, have invented certain new and useful Improvements in Reducing-Valves, of which the following is a specification.

This invention relates to valves for regulating the discharge of a fluid of any given initial pressure (which may be variable) in such a manner as to automatically restrict the pressure of the discharge to some predetermined reduced pressure.

15 In the accompanying drawings, Figures 1 and 2 illustrate a reducing-valve embodying our improvements, Fig. 1 being a vertical section and Fig. 2 a side elevation with certain parts in section. Fig. 3 is a vertical section of the valve-casing on a plane at right angles to that employed in Fig. 1. Fig. 4 is a view similar to Fig. 3, illustrating a modification hereinafter more particularly referred to.

According to our invention, the main valve 25 A for controlling the passage of the fluid is of the equilibrium type, and consists of two disk-shaped heads a a^* , arranged at a suitable distance apart and either formed integrally with the valve stem or body a' or rigidly attached thereto. Each head is preferably formed or provided with wings a^2 , which work in seatings or cut-off rings a^3 a^4 and serve as guides. The seatings or cut-off rings a^3 a^4 are maintained at a suitable distance apart by means 35 of arms a^5 , which constitute a skeleton frame. The heads a a^* of the valve are larger in diameter than the bore of the seatings, so that the former take a bearing upon the faces of the latter. In order to admit of the parts being assembled, one of the seatings a^3 is formed as a loose ring, and one of the heads a^* is secured or otherwise attached to the valve stem or body.

The fluid the pressure of which is to be reduced is admitted by way of openings a^6 between the two heads a a^* , and when the valve A is open, as shown in Figs. 1 and 3, escapes in opposite directions between a a^* and their respective cut-off rings or seatings a^3 a^4 .

50 The valve A is connected, by means of a stem a^7 , to the long arm b of a lever B, preferably of the first order, the said stem and lever being inclosed within a casing b' . The opposite or short arm b^* of the lever is connected, by 55 means of a rod c , to a flexible diaphragm C, whereof the upper side is inclosed within a

casing c' , attached to the cover a^8 of the main-valve casing, while the lower side is supported upon a piston D. This piston is carried by a nut c^2 , applied to the lower end of the spindle c , the extremity of the latter resting upon a yoke d , the ends of which engage with suspending-rods d' d'' , borne by spiral or other suitable springs d^2 d'' . The pressure of the springs d^2 d'' , although capable of variation 60 for purposes of adjustment, are normally capable of exercising a resistance equivalent to the pressure of the fluid acting on the inclosed face of the diaphragm C. Under such circumstances both the main valve A and the 65 diaphragm C are respectively in equilibrium; but the respective movements of these two parts vary in the ratio of the lengths of the two arms b b^* of the lever B, to which they are severally attached. Thus the movement 70 of the valve A may be considerable, so as to afford a full-way passage for the fluid, while the movement of the diaphragm C is relatively small and admits of nearly the whole of its area being constantly borne by the spring-supported piston D. Owing, moreover, to the small extent of the movement of the diaphragm, the pressure exerted by the springs d^2 d'' remains practically constant. It will be 75 obvious that the design may be modified in 80 such a manner as to admit of the pressure on the diaphragm C being counterbalanced by means of weights instead of springs.

When a valve of the equilibrium type, such as above referred to, is employed, the initial 85 pressure is admitted between the heads a a^* thereof, passes to the reduced-pressure side, and, entering the casing b' by way of the passage b^2 , surrounding the valve-stem a' , finds its way to the inclosed face of the diaphragm 90 C. Upon the reduced pressure becoming so far augmented as to exceed the load on the spring-supported diaphragm the latter is deflected, with the effect that the main valve A is partially or wholly closed.

It will be obvious that the apparatus described may be made applicable for use as a surplus valve by transposing the inlet and outlet and inverting the valve with its seatings.

105 Among other advantages resulting from the construction described the chamber in which the diaphragm is mounted remains comparatively cool, its distance from the valve-chamber being such that the transmission of heat by conduction is for the most part prevented. Moreover, the diaphragm-

chamber is not liable to collect dirt or sediment. It remains charged with the water of condensation and is only exposed to the reduced pressure as distinguished from the initial pressure of the steam. Any sudden movement of the diaphragm, and consequently of the valve, is avoided by reason of the diaphragm-chamber being nearly closed, thus preventing the rapid discharge of the water of condensation.

What we claim as our invention, and desire to secure by Letters Patent, is—

1. In a reducing-valve, the combination with a main controlling-valve of the equilibrium type, having two heads of equal diameter, and cut-off rings whereon the heads respectively seat, of a rocking-lever connected as to one arm with the said valve and as to the other arm with a reacting diaphragm;

the latter being exposed on the lever side to 20 the pressure of the "reduced-pressure" steam, and on the opposite side to the atmosphere.

2. In a reducing-valve, the combination, with a main controlling-valve of the equilibrium type having two heads of equal diameter, 25 of a skeleton frame formed with two cut-off rings whereon the heads respectively seat; one of the heads of the valve being separable and one of the cut-off rings being detachable.

In testimony whereof we have signed our 30 names to this specification in the presence of two subscribing witnesses.

JOHN DEWRANCE.
GEORGE HENRY WALL.
